UNITED STATES PATENT OFFICE.

ANTOINE FRANCE, OF LIEGE, BELGIUM.

PLANT FOR WASHING COAL AND OTHER MINERALS.

Application filed November 7, 1927; Serial No. 231,649, and in Belgium February 24, 1927.

The present invention relates to an improvement in plants for washing coal and other minerals, of the type comprising one or more horizontal or slightly inclined launders in which the materials are sorted by order of their respective densities, through the action of an alluvium forming stream whereby the dense particles are conveyed in the lower parts and the light particles in the upper parts, the bottom of the launder or launders being provided with slots in which the particles moving along the lower part of the launder can drop. In order to avoid the dropping of light particles into the slots intended normally to allow material of a determined minimum density to pass, it is desirable that the dense layer formed and travelling upstream of these slots, be freed from light particles, and that said layer shall have such a thickness and that said thickness shall be sufficiently homogeneous as to prevent light particles being driven with the dense particles through the slots. On the other hand, the material which is to pass beyond the last slot should be cleansed to the required extent, and freed from particles that could alter its composition. Now, the circumstances which determine the stage of layer-formation are liable to vary on account of the general outline or shape of the effective transverse section of the launder, and according to the velocity acquired by the alluvium forming stream which is moreover itself governed by the width and also by the shape given to the effective section of the launder.

The present invention relates to a launder, the effective transverse section of which varies in shape at several points along a portion comprised between two successive slots, thus providing for a sequence of the phenomena in the order necessary for obtaining the required sorting or stratification inside the launder. In accordance with requirements, a number of portions of launder, each being a portion comprised between two succeeding slots, may be given a similar shape, or a dissimilar shape if it be necessary, say, for example, by reason of variation in the average density of the bulk of material driven beyond each slot, due to the successive elimination of dense particles. The invention further relates to variation of the effective transverse section of the launder, at various points of a portion of it situated upstream of, and close to the first slot,

and relates to the various embodiments which are hereinafter set forth by way of examples, with reference to the accompanying drawings.

In these drawings, Figures 1 and 2 are plans of parts of launders having, at different points along them, various shapes and sections.

Figure 3 is a vertical transverse sectional view of a launder, the effective width of which is variable for different levels.

The launder illustrated by way of example in Figure 1 comprises first a portion, the effective section of which narrows progressively or converges in a downstream direction, then a portion having an effective section of uniform width, extending from a point situated upstream of a slot 3 to a point downstream of the slot 3, next a portion having a section which diverges, still in a downstream direction and is followed by a portion of uniform width, which in turn is followed by a converging portion ending at a point somewhat upstream of the next slot 3' and is continued by a portion of uniform width ending at a point downstream of the slot 3' last referred to. Under these slots discharge pockets 4 may be eventually arranged.

An arrangement such as that above described will lend itself to the following sequence of phenomena: From A to B the layer of dense material travelling along the bottom of the launder will get gradually thicker, owing to the gradual narrowing of the section; in this portion of the launder, the arrangement is also favourable to the separation of any light particles that would be driven along in the bedding of dense material:—from B to C, the dense material will have its thickness regularized, as a result of the uniform section throughout that portion of the launder; by these means it is possible to combine all the favourable conditions for separating out the dense products freed of light particles, since a sufficiently thick and uniform layer of dense products is formed in front of the slot and moreover because the light particles are separated so much better from the bed of dense products because they are, upstream and above the apparatus, drawn by a stream of greater velocity due to the narrowing of the launder in this position; then, from C to D, any dense particles which may have been drawn along in the upper part of the stream

will be deposited, an effect obtained under co-operation of a spreading of the material, and also fostered by the decreased velocity of the alluvium forming stream, due to the 5 diverging or widening of the launder in a downstream direction; from D to E, the formation of layers will become regularized as a result of the uniformly shaped section throughout that portion of launder; then, 10 from E to F the layer of dense material will again get thicker and the separation of any light particles drawn along with the dense material will be fostered.

Figure 2 shows a launder wherein the 15 above explained arrangement, which is symmetrical relative to the axis, has been replaced by the provision of a unilateral arrangement, the device having, at one side only, a shape like that above described, while 20 the other side is uniform along the length of the launder. Although a technical result similar to the foregoing will be obtained with this arrangement, it is, of course, less efficient than the bilateral arrangement.

Figure 3 is a cross section, wherein the 25 effective section 1 of the launder is narrowest near its bottom, then diverges upwards, reaching its maximum width 2 at the top; such a cross-sectional variation can be of 30 profitable use in combination with the longitudinal variation, in order to give the launder a maximum capacity while providing for formation of a sufficiently thick bed-
ding of schistous elements.

It should be understood that all of these 35 embodiments are mere examples of carrying the invention into practice, and that, according to the quality of materials to be dealt with, or to the kind of sorting required, or the degree of perfection desired, 40 launders of a width varying lengthwise, in different ways, can be used; thus, if required sides having surfaces which are curved, rounded, winding or stepped and so on, can be used.

45

I claim:

A launder for classifying coal and other minerals according to specific gravity by means of a liquid conveying stream, which conveys the dense products to the lower 50 parts and the light products to the upper parts of the launder, in the bottom of which are arranged transverse slots for discharging the dense products moving in the lower parts of the launder, the inner section of 55 said launder varying in the downstream direction so as to comprise consecutively a portion gradually widening from a point located downstream of a slot, a relatively wide portion of constant section, a portion 60 gradually narrowing up to a point located upstream of the next slot and a relatively narrow portion of constant section extending from a point upstream to a point downstream of the last mentioned slot.
